UNITED STATES PATENT OFFICE.

JOHN GRIMSHAW, OF PATERSON, NEW JERSEY.

DESIGN FOR A HANDKERCHIEF.

SPECIFICATION forming part of Design No. 11,725, dated April 13, 1880.

Application filed February 7, 1880. Term of patent 3½ years.

To all whom it may concern:

Be it known that I, JOHN GRIMSHAW, of Paterson, in the county of Passaic and State of New Jersey, have invented a new and original Design for a Handkerchief, of which the following is a specification.

This invention relates, first, to the new ornamentation of the body of a handkerchief; and, second, to the new ornamentation of the border of the same.

The accompanying photograph illustrates my new design.

The body A of the handkerchief is crossed in both directions by stripes *a*, and, alternating with the said stripes, by stripes *b*, which are composed of numerous narrow longitudinal stripes, so that the stripes *a b* running in one direction are at right angles to the stripes *a b* running in the other direction.

The border B of the handkerchief is composed of stripes *d e f*, of different widths, parallel to the sides of the handkerchief, each of which is composed of narrow longitudinal stripes, and the border-stripes *d e f* are crossed at right angles by stripes *g h*, which are prolongations respectively of body-stripes *a b*.

I claim—

1. The design for the body of a handkerchief, which consists of the stripes *a* and stripes *b*, composed of numerous narrow longitudinal stripes, and arranged so that the stripes *a b* running in one direction are at right angles to stripes *a b* running in the other direction, substantially as described, and shown in the accompanying illustration. 30

2. The design for the border of a handkerchief, which consists of the parallel stripes *d e f* and stripes *g h*, prolonged from the body-stripes *a b* and crossing stripes *d e f* at right angles, substantially as described, and shown 40 in the accompanying illustration. 35

3. The design for a handkerchief which consists of the body A, crossed at right angles by stripes *a b*, and border B, composed of parallel stripes *d e f* and right-angular stripes *g h*, prolonged from the body-stripes *a b*, substantially as described, and shown in the accompanying 45 illustration. 45

JOHN GRIMSHAW.
